FRANK RIEBER, OF SAN FRANCISCO, CALIFORNIA, ASSIGNOR, BY MESNE ASSIGNMENTS, TO RIEBER LABORATORIES, OF SAN FRANCISCO, CALIFORNIA, A CORPORATION OF CALIFORNIA.

APPARATUS FOR EXCITING ROENTGEN-RAY TUBES.

1,305,495.

Specification of Letters Patent. Patented June 3, 1919.

Application filed January 29, 1917. Serial No. 145,088.

To all whom it may concern:

Be it known that I, FRANK RIEBER, a citizen of the United States, and a resident of the city and county of San Francisco and 5 State of California, have invented certain new and useful Apparatus for Exciting Roentgen-Ray Tubes, of which the following is a specification.

The invention relates to apparatus for 10 producing high tension unidirectional current for the excitation of Roentgen ray tubes.

An object of my invention is to supply 15 high tension unidirectional current for exciting said X-ray tubes and maintain the potential of the said unidirectional current at substantially any desired value irrespective of the resistance of the Roentgen tube.

A further object of my invention is to 20 provide means whereby this potential applied to the Roentgen tube may be altered at will during the operation of the tube without discontinuing the flow of current during said alteration or without changing 25 the operating characteristics of the apparatus during such alteration. The excitation of Roentgen tubes by the so-called interrupterless or transformer type outfit has heretofore been controlled in 30 one of two ways. In apparatus heretofore used the said interrupterless apparatus consisted primarily of a source of alternating potential, a transformer adapted to increase the potential of said alternating source to 35 a point where it may be applied for the production of Roentgen-rays and means for converting this high potential alternating current into high potential direct current.

The controlling means used for varying 40 the power and potential applied to the Roentgen tube consists either of a resistance or rheostat inserted in series in the primary circuit of the high tension transformer aforesaid or of an auto-transformer or other 45 device receiving the input or line alternating potential and delivering a potential which may be varied and which is applied to the primary terminals of the high tension transformer.

50 Auto transformers or controls of this last-described class, have a distinct advantage in that they have low inherent electrical impedance and therefore supply an approximately uniform alternating potential irre-

spective of the total load imposed upon the 55 apparatus by the Roentgen tube. As heretofore constructed, however, these auto transformers have the distinct disadvantage that the flow of current through the apparatus must be interrupted during the time 60 that the potential delivered from the auto-transformer is being varied.

By the apparatus of my invention this defect is obviated and it becomes possible to make any desired alteration in the potential 65 delivered from the auto transformer (said alteration causing a corresponding alteration in the high potential delivered from the high tension transformer) without interrupting the flow of the current. 70

In the accompanying drawings I have illustrated an embodiment of my invention in diagrammatic form, but it is to be understood that I do not limit myself to the embodiment shown, since the invention as set 75 forth in the succeeding claims may be embodied in a plurality of forms.

Referring to said drawings:

Figure 1 is a diagrammatic representation 80 of the apparatus of my invention.

Figs. 2, 3 and 4 are diagrammatic representations of different positions of the potential changing contacts of the apparatus.

Fig. 5 is a diagrammatic representation 85 of one arrangement of the auto transformer terminals and means for moving the potential changing contacts over them.

The winding 2 of the auto transformer is connected at its ends to power leads 3-4 which extend to a suitable source of alternating potential. The winding 2 is provided at one end with a common terminal 5 and at spaced points along the winding with taps which are connected to the plurality of spaced terminals 6-7-8-9, etc., so that a 95 variable electromotive force may be obtained by shifting a contact from one terminal 6-7-8-9, etc., to another. The terminal 5 is connected to one side of the primary winding 12 of a high potential transformer 13 and the other end of the primary winding is immediately connected to one of the terminals 6-7-8-9, etc., the potential between the terminal 5 and the chosen terminal 6-7-8-9 being delivered to the primary 100 winding. A voltmeter 14 may be provided for measuring the delivered potential and a switch 15 may be provided for conveniently 105

interrupting the circuit when desired. The secondary winding 16 of the transformer delivers alternating current at high potentials to a suitable rectifying device 17 and the unidirectional current therein produced is conducted to the Roentgen tube 18.

Means are provided for varying the potential delivered from the auto transformer without interrupting the current through the tube. Arranged between the terminals 6—7—8—9 and one side of the primary transformer winding 12 is a small transformer winding 21 which is connected at its center to the end of winding 12 and which is provided on its ends with contacts 22—23 which slidably engage one or two of the terminals 6—7—8—9 at one time. In Figs. 2, 3 and 4 I have shown the small transformer contacts in different positions with respect to the terminals 6 and 7, illustrating the method of varying the potential delivered from the auto transformer without interrupting the current. In Fig. 2, the contacts 22 and 23 are in engagement with the terminals 6 and 7 respectively. In this position the current flows from terminal 6 through the small transformer winding 21 to terminal 7, thereby exciting the small transformer. The central terminal 24 on the small transformer will then have a potential midway between the potentials of terminals 6 and 7 and this potential is effective in the winding 12. By moving the contact 22 out of engagement with terminal 6 and allowing contact 23 to remain in engagement with contact 7, the current will flow to the winding 12 through one path of the small transformer. In this position, the inherent impedance of the small transformer is interposed in the circuit, but with proper construction, this is so slight that the alteration of the operating characteristics of the apparatus is inappreciably small.

In the position shown in Fig. 4, both contacts 22 and 23 are in engagement with terminal 7, so that one-half of the current passes each way through the small transformer, the resultant impedance of which therefore becomes zero. The voltage delivered from the auto-transformer has, therefore, been varied without interrupting the flow of current and without appreciably altering the operating characteristics of the apparatus during such variation. The movement of the contacts 22—23 may be continued throughout the entire range of the terminals 6—7—8—9, etc., of the auto transformer in order to obtain the desired potential at the tube.

In practice, the terminals 6—7—8—9, etc., may be arranged in an arc and the contacts 22—23 carried on an arm 25, so that by rotation of the arm, the contacts and terminals will assume successively the positions indicated in Figs. 2, 3 and 4.

I claim:

1. In an apparatus for producing high potential unidirectional electric current, a source of alternating potential, means for transforming said potential to another potential, means for varying said transformed potential without interrupting the continuity of the electric current, means for transforming the variable potential to a much higher potential, and means for converting the resultant high potential alternating current to high potential unidirectional current. 70

2. The combination with a Roentgen ray tube, of a circuit therefor, an auto-transformer in said circuit having a plurality of taps and a subsidiary auto-transformer having end taps in movable engagement with said first mentioned taps, said subsidiary auto-transformer being connected in 85 said circuit and said end taps being arranged so that the voltage of the circuit may be varied without opening the circuit. 80

3. In an apparatus for producing high potential unidirectional current, a source of 90 alternating current of substantially constant potential, means having inherently low impedance for transforming said potential to a different potential, means for varying the transformed potential without interrupting 95 the continuity of the electric current, means for transforming the resultant potential to a higher potential and means for converting the higher potential alternating current to high potential unidirectional current. 100

4. In an apparatus for producing high potential unidirectional current, a source of alternating current of substantially constant potential, an auto transformer in circuit with said source, a plurality of taps on said auto transformer, a high potential transformer having its primary connected at one side to one side of the auto transformer and at the other side to said taps, a small transformer interposed between said primary and said taps and having the center of its winding connected to said primary and the ends of its windings movable into contact with the successive taps, a secondary for said high tension transformer and means connected to said secondary for converting the high potential alternating current to high potential unidirectional current. 110

5. In an apparatus for producing high potential unidirectional current, an auto transformer having a plurality of taps, terminals connected to said taps, a small transformer having the two ends of its winding movable in contact with said terminals, a high potential transformer having its primary connected to said auto transformer and to the middle of said small transformer winding and a current-converting device connected to the secondary of said high tension transformer. 120

6. The combination with a source of alternating current potential of an auto-transformer in circuit with said source, a plurality of taps on said auto-transformer, a small auto-transformer having the ends of its winding movable into contact with the successive taps and a circuit connecting the center of the small transformer winding

and the end of the first auto-transformer winding.

In testimony whereof, I have hereunto set my hand at San Francisco, California, this 15th day of January, 1917.

FRANK RIEBER.

In presence of—
H. G. PROST.
